UNITED STATES PATENT OFFICE.

JONAS NORTHROP, OF HOPEDALE, MASSACHUSETTS, ASSIGNOR TO HOPEDALE MANUFACTURING COMPANY, OF HOPEDALE, MASSACHUSETTS, A CORPORATION OF MASSACHUSETTS.

WARP STOP-MOTION FOR LOOMS.

1,252,292.

Specification of Letters Patent.

Patented Jan. 1, 1918.

Application filed June 7, 1913. Serial No. 772,447.

To all whom it may concern:

Be it known that I, JONAS NORTHROP, a citizen of the United States, residing at Hopedale, in the county of Worcester and 5 State of Massachusetts, have invented certain new and useful Improvements in Warp Stop-Motions for Looms; and I do hereby declare the following to be a full, clear, and exact description of the invention, such as 10 will enable others skilled in the art to which it appertains to make and use the same.

The present invention relates to an improvement in warp stop motions for looms. The object of the invention is to reorganize 15 and improve the construction, organization and mode of operation of warp stop motions, and to these ends the invention consists in the warp stop motion hereinafter described and particularly defined in the claims.

20 In the accompanying drawings illustrating the preferred form of the invention, Figure 1 is an end elevation of a loom showing the motion applied thereto and omitting elements non-essential to its illustration;

25 Fig. 2 is an enlarged elevation of a portion of Fig. 1 showing devices immediately connected with the shipper for stopping the loom; Fig. 3 is a similar view, the frame of the loom being removed for the purpose of

30 more clearly illustrating the construction of the parts; Fig. 4 is a front elevation of the left-hand portion of the loom showing these parts as they appear from the front of the loom; Fig. 5 is a plan of the knock- 35 off bar and showing its position with relation to the shipper lever; Fig. 6 is an enlarged portion of the drop wire supporting frame showing the drop wires and the feeler bar; and Fig. 7 is a plan view of a portion 40 of the same.

The illustrated embodiment of the invention is described as follows:—

The loom frame 1, the cam shaft 2, the lay 3 and the breast beam 4 are or may be 45 of the usual form. The warp leads from the warp beam 5, over the whip roll 6, over the lease rods, through the heddles, over the breast beam and to the take-up, in the usual manner. The warp detector devices 50 consist of drop wires 7 held in position by rods 8 and 9 located between the lease rods 10 and 11. The lower ends of the drop wires are located between the angle bars 12 and 13 which unite the end frames 14. The 55 feeler 15 is mounted on arms 16 carried by

the rock shaft 17 which is oscillated by the arm 18, in turn actuated by the link 19. The warp detector devices are supported from the bars 20 which are received in the 60 housings 21 of the end frames 14, being secured thereto by set screws. The bars 20 find support from the frame of the machine in the housings 22 mounted upon the upper ends of the rods 23, carried in the housings 24 mounted in the frame of the machine, the 65 rods 23 being secured in the housings 24 by means of set screws, and the bars 20 being secured in the housings 22 by means of set screws. This supporting means affords 70 provision for adjustment of the detector devices vertically, horizontally and angularly, so as to adapt the detector device to different looms. At the front of the loom the link 19 carries a notch bar 30 which is adjustably secured at 31 to the link 19. The 75 notch bar 30 is supported on the stud 32 projected laterally from the lower end of the actuating arm 33 pivoted at its upper end in the casting 34, secured to the breast beam 4 of the loom. The upper end of the 80 arm 33 is provided with a head 36, and a pin 37 supported in the ears 38 of the casting 34 affords a pivotal support for the arm 33. The arm 33 is oscillated upon its pivotal 85 support by the cam lever 39 of the weft stop motion. Upon the side of the cam lever 39 is secured a casting 40 having at its upper end a pin 41 which engages a slot 42 in the arm 33. It will thus be seen that the oscillations of the cam lever through the 90 pin 41 secured thereto impart correspondingly timed oscillations to the arm 33, and that these oscillations impart a reciprocating movement to the link 19. The means for connecting the link 19 to the arm 33 are 95 such that when a drop wire falls and arrests the motion of the feeler, the link 19 is thereby arrested while the actuating arm moves on. This connecting device consists of a slide bar 50 which is received in a hole 100 in a boss 51 which projects from the side of the actuating arm 33. The upper end of the slide bar 50 is pivotally connected to the arm 52 secured to the knock-off bar 53. The lower end of the slide bar 50 projects below 105 the boss 51 and normally engages the notch 54 in the upper side of the notch bar 30. The oscillations of the actuating arm 33 impart reciprocating movements to the link 19 because the weight of the slide bar 50 is 110

such as to hold its lower end in engagement with the notch 54. When, however, a drop wire falls and arrests the feeler 15, the link 19 is held thereby from motion and the further movement of the actuating arm 33 in the direction in which it is moving at the time causes the slide bar 50 to be lifted out of the notch 54, thereby moving it endwise and causing it to rock the knock-off bar 53. 5 Upon the end of the knock-off bar 53 is secured the dagger 55 which normally occupies the position indicated in Fig. 2; when the knock-off bar 53 is oscillated by means of the slide bar 50 it lifts the dagger 55 into 10 operative position, bringing it into position to be engaged by the bunter 56 secured to the lay. The knock-off bar 53 is supported in a bracket 57 which is attached to the breast beam. This bracket 57 is provided 15 with a slot 58 and the knock-off bar 53 is received in this slot. This slot is horizontal, as seen in Fig. 2, and the knock-off bar normally occupies the rear end of this slot, as shown in Fig. 5. The shipper lever 59, 20 when in running position, occupies the position shown in Fig. 5, being held in this position by the notch in the rear side of the slot 60 in the usual manner. A spring 61 normally tends to hold the knock-off bar 53 25 in its rearmost position, as shown in Fig. 5. Now, therefore, when the slide bar 50 is raised, it rocks the knock-off bar so as to bring the dagger 55 in opposition to the bunter 56, and upon the next beat of the 30 lay the bunter strikes the dagger and drives the knock-off bar 53 forwardly, thereby releasing the shipper 59 from engagement with the notch in the slot 60, and through the usual means, such as the lever 63 and 35 shipper 62, throws the belt from the fast to the loose pulley, thereby stopping the loom. 40

It is to be observed that the feeler has a broad flat surface on top and that it is shown in Fig. 6 at the extreme right-hand limit of its throw. If now, one of the rear drop wires 7 falls, the feeler in its rearward motion will be arrested thereby and the slide bar 50 will be lifted from the notch 54 in the notch bar, thereby lifting the dagger 45 into the path of movement of the bunter, and upon the next forward beat of the lay, the loom will be stopped. This lifting of the slide bar 50 would occur during the backward swing of the actuating arm 33, the 50 lower end of the slide bar 50 riding along on the upper surface of the notch bar 30. Upon the next return or forward movement of the arm 33, the link 19 moves forwardly with the actuating arm by reason of the 55 friction between the slide bar 50 and the upper surface of the notch bar 30, and such movement of the link 19 continues until the feeler reaches the limit of its throw, which holds the link 19 from further movement, permitting the slide bar 50 to move over the sur-

face of the notch bar 30 until it reaches the notch. This movement of the link 19 first operates to move the feeler to free the fallen drop wire, and thereafter operates to move the feeler to the other extreme of its movement, whereupon it is arrested and the link is held while the slide bar is moved along over the surface of the notch bar until it engages the notch and thereby restores the parts to their normal operative positions. 70 The rear drop wire engages the feeler in its rearward motion and the wires of the front row of drops engage the feeler in its forward movement. The broad, flat surface of the top of the feeler operates so as to prevent the drops from engaging the feeler during the time that the feeler is directly under the drops. If, for example, a drop should fall while the feeler was under it, it would be supported upon the upper surface of the 75 feeler until the feeler had moved out from under it, whereupon it would fall into position to be engaged by the feeler upon its next stroke. It is to be observed that the arrest of the feeler takes place while the lay is 80 at or near its back center, and that the first result of the arrest of the feeler is to throw the stopping mechanism into stopping condition, that is to say, it moves the dagger 85 into position to be struck by the bunter, 90 and on the next forward beat of the lay, the shipper is released and the loom is stopped. The loom may, therefore, be said to have means acting automatically to indicate a 95 failure of warp on the back stroke of the 100 lay and to trip the stopping means on the next forward beat of the lay. The operation of the mechanism is the same whether the feeler is arrested on its forward or backward movements; the slide bar moving to the 105 one side or the other of the notch, as the case may be. There is no disconnection of the link 19 from the slide bar 50, the friction between them being sufficient at all times to 110 actuate the link except when the latter is arrested by a drop wire.

This stop motion is simple in construction and therefore cheap and adapted for attachment to or incorporation in looms at a minimum of expense. This stop motion is also 115 simply organized in the relative arrangement of its parts and efficient in operation, which render it not liable to get out of order. Owing to the simplicity of construction and its organization very largely, the operation 120 of the motion is simple and certain. The stopping of the loom upon the fall of a drop wire is accomplished by the lifting of a comparatively light slide bar which thereby 125 rocks the knock-off bar so as to bring the dagger in the position to be struck by the bunter. The main stopping element, the shipper lever, is thereby moved to stop the loom by the intervention of only a single element, namely, the knock-off bar between 130

it and the lay which effects the reengagement of the shipper lever, and the knock-off bar itself is actuated by a single element which is lifted by the arrest of the feeler.

5 Having thus described the specific embodiment of the invention, which is not limited to such embodiment as it may be embodied in other forms, what is claimed is:—

1. A warp stop motion for looms having, 10 in combination, warp detectors, a feeler, a notch-bar connected with the feeler, actuating means therefor, a knock-off bar and a device for connecting the actuating means with the notch-bar movable longitudinally 15 when the notch-bar is arrested upon the fall of a warp detector to move the knock-off bar into position for knocking off the loom.

2. A warp stop motion for looms having, 20 in combination, warp detectors, a feeler, knock-off means, connections between the feeler and knock-off means including a notch-bar connected with the feeler adapted to move forwardly and backwardly, and actuating means for the notch-bar connected 25 with the knock-off means, said notch-bar and its actuating means having provision for permitting the notch-bar to remain stationary on the backward movement of its actuating means when a fallen warp detector on 30 warp breakage is in the path of movement of the feeler, and for permitting the notch-bar to move forward with its actuating means on the next forward movement of the latter.

3. A warp stop motion for looms having, 35 in combination, warp detectors, a feeler, a shipper lever, a knock-off bar movable laterally to knock off the shipper lever and movable angularly to bring its dagger into 40 position to be struck by a bunter, a cam lever, an oscillating actuating arm connected with and actuated by the cam lever, a slide bar slidably attached to the actuating arm and affording a connection not only between 45 such actuating arm and the feeler, but also between the feeler and the knock-off bar, substantially as described.

4. A warp stop motion for looms having, 50 in combination, warp detectors, a feeler, actuating means therefor, a shipper lever, knock-off means for the shipper lever, longitudinally moving means connecting the feeler with the actuating means and adapted, upon the arrest of the feeler, to move the 55 knock-off means into position for knocking off the shipper and a slide bar connection between the longitudinally moving means and the actuating means, having provision for movement relative to both upon the occurrence of warp breakage.

5. A warp stop motion for looms having, 60 in combination, warp detectors, a feeler, a notch-bar connected therewith, actuating means therefor, a knock-off bar, and connecting means between the notch-bar and the

knock-off bar having provision for engaging the notch in the notch-bar while the loom is operating normally and for being disengaged from the notch and sliding along the notch-bar when the notch-bar is arrested 70 upon warp breakage.

6. A warp stop motion for looms having, 75 in combination, warp detectors, a feeler, knock-off means, connections between the feeler and knock-off means including a notch-bar connected with the feeler adapted to move forwardly and backwardly, and actuating means for the notch-bar connected with the knock-off means, said notch-bar and its actuating means being constructed and 80 arranged to permit the actuating means to move backwardly relatively to the notch-bar when a fallen warp detector on warp breakage is in the path of movement of the feeler and having provision for permitting the actuating means to move the notch-bar with it on its next forward movement.

7. A warp stop motion for looms having, 90 in combination, warp detectors, a feeler, knock-off means, connections between the feeler and knock-off means including a notch-bar connected with the feeler adapted to move forwardly and backwardly, and actuating means for the notch-bar connected with the knock-off means, said notch-bar and 95 its actuating means having provision for permitting the notch-bar to remain stationary on the forward movement of its actuating means when a fallen warp detector on warp breakage is in the path of movement 100 of the feeler and for permitting the notch-bar to move backward with its actuating means on the next backward movement of the latter.

8. A warp stop motion for looms having, 105 in combination, warp detectors, a feeler, knock-off means, connections between the feeler and knock-off means including a notch-bar connected with the feeler adapted to move forwardly and backwardly, and actuating means for the notch-bar connected with the knock-off means, said notch-bar and 110 its actuating means having provision for permitting the notch-bar to remain stationary on the backward movement of its actuating means when a fallen warp detector on warp breakage is in the path of movement of the feeler, and for permitting the notch-bar to move forward with its actuating means on the next forward movement of the latter, said notch-bar and its actuating 115 means having further provision for permitting the notch-bar to remain stationary on the forward movement of its actuating means when a fallen warp detector on warp breakage is in the path of movement of the feeler and for permitting the notch-bar to move backward with its actuating means on the next backward movement of the latter.

9. A warp stop motion for looms having, 120 125

in combination, warp detectors, a feeler, knock-off means, connections between the feeler and knock-off means including a notch-bar connected with the feeler adapted 5 to move forwardly and backwardly, and actuating means for the notch-bar connected with the knock-off means, said notch-bar and its actuating means being constructed and arranged to permit the actuating means to 10 move forwardly relatively to the notch-bar when a fallen warp detector on warp breakage is in the path of movement of the feeler and having provision for permitting the actuating means to move the notch-bar with it 15 on its next backward movement.

10. A warp stop motion for looms having, in combination, warp detectors, a feeler, knock-off means, connections between the feeler and knock-off means including a 20 notch-bar connected with the feeler adapted to move forwardly and backwardly, and actuating means for the notch-bar connected with the knock-off means, said notch-bar and its actuating means being constructed and 25 arranged to permit the actuating means to move backwardly relatively to the notch-bar when a fallen warp detector on warp breakage is in the path of movement of the feeler and having provision for permitting the actuating means to move the notch-bar with it on its next forward movement, said notch-bar and its actuating means being further 30 constructed and arranged to permit the actuating means to move forwardly relatively to the notch-bar when a fallen warp detector on warp breakage is in the path of movement of the feeler and having further provision for permitting the actuating means to move the notch-bar with it on its next backward movement.

11. A warp stop motion for looms having, in combination, warp detectors, a feeler, knock-off means, and connections between the feeler and the knock-off means including 45 a notch-bar connected with the feeler and a notch-bar actuating means connected with the knock-off means having provision for engagement with the notch in the notch-bar to impart a reciprocatory movement to the 50 notch-bar during normal weaving, and for disengagement from the notch to permit the notch-bar to remain stationary when the feeler encounters a fallen detector.

12. A warp stop motion for looms, having 55 in combination, warp detectors, a feeler, knock-off means, connections between the feeler and knock-off means including a notch-bar and connections between the feeler and notch-bar, and means for actuating the 60 notch-bar including a slide bar connected with the knock-off means, said slide bar being adapted to be disengaged from the notch in the notch-bar upon the occurrence of warp breakage and to engage the notch in 65 the notch-bar on the next movement of the

notch-bar actuating means in the direction opposite to that in which the notch-bar was moving on the occurrence of warp breakage.

13. A warp stop motion for looms having, in combination, warp detectors, a feeler, 70 knock-off means, and connections between the feeler and the knock-off means including a reciprocatory bar connected with the feeler, means connected with the knock-off means constructed and arranged to impart 75 a reciprocatory movement to the bar during normal weaving and to permit the bar to remain stationary when the feeler encounters a fallen warp detector, and means for actuating the bar reciprocating means. 80

14. A warp stop motion for looms having, in combination, warp detectors, a feeler, knock-off means, and connections between the feeler and the knock-off means including a reciprocatory member connected with 85 the feeler, an oscillatory arm connected with the knock-off means for supporting and imparting reciprocating movements to the reciprocatory member, a cam actuated lever, and a pin and slot connection between the 90 lever and the arm.

15. A warp stop motion for looms having, in combination, warp detectors, a feeler, knock-off means, and connections between the feeler and the knock-off means including a reciprocatory notch-bar connected with the feeler, an oscillatory arm, a slide bar on the arm connected with the knock-off means and 95 yielding held in engagement with the notch in the notch-bar during normal weaving, a lever, actuating means therefor, and connections between the lever and the arm. 100

16. A warp stop motion for looms having, in combination, warp detectors, a feeler, knock-off means, and connections between 105 the feeler and the knock-off means including a reciprocatory notch-bar connected with the feeler, an oscillatory arm, a slide bar on the arm connected with the knock-off means having provision for engagement with the notch in the notch-bar during normal weaving and having provision for disengagement from the notch when the feeler encounters a fallen warp detector, a lever, actuating means therefor, and connections between the lever 110 and the arm. 115

17. A warp stop motion for looms having, in combination, a cam actuated lever, an oscillatory arm, pin and slot connections between the lever and the arm, a lay, a bunter 120 thereon, a slide bar mounted on the arm carrying a knock-off bar, a dagger on the knock-off bar normally out of the path of the bunter, a notch-bar supported by the arm and reciprocated thereby through the engagement of the slide bar with the notch in the notch bar during regular weaving, a feeler, connections between the notch-bar and the feeler, and warp detectors, the whole being constructed and arranged to move the 125 130

dagger into the path of the counter to cause loom stoppage when the feeler encounters a fallen detector.

18. A warp stop motion for looms having, 5 in combination, warp detectors, a feeler, a notch-bar, connections between the feeler and the notch-bar, an oscillatory arm for supporting the notch-bar, a slide bar mounted on the arm yieldingly held in engagement 10 with the notch in the notch-bar during normal weaving, a knock-off bar connected with the slide bar, a dagger supported on the knock-off bar, a lay, a bunter carried thereby, the dagger being out of the path of 15 movement of the bunter during normal weaving, a cam actuated lever, and pin and slot connections between the lever and the oscillatory arm whereby reciprocatory movements are imparted to the notch-bar, the 20 whole being constructed and arranged to cause the slide bar to be disengaged from the notch in the notch-bar to place the dagger in the path of movement of the bunter when the feeler on warp breakage encounters a 25 fallen detector.

19. A warp stop motion for looms having, in combination, warp detectors, a feeler, a reciprocatory notch-bar connected with the feeler, knock-off means normally in inoperative position, and actuating means for the 30 notch-bar constituting connections between the latter and the knock-off means having provision for placing the knock-off means in operative position when the feeler encounters a fallen warp detector. 35

20. A warp stop motion for looms having, in combination, warp detectors, a feeler, knock-off means, and connections between the feeler and the knock-off means operating when the feeler encounters a fallen detector 40 to cause the knock-off means to stop the loom, comprising a reciprocatory bar connected with the feeler and actuating means for the bar connected with the knock-off means.
